UNITED STATES PATENT OFFICE.

HYDESABURO OHASHI, OF NEW YORK, N. Y., ASSIGNOR TO HYDESABURO OHASHI & CO.,
INC., OF NEW YORK, N. Y., A CORPORATION OF DELAWARE.

INKING ATTACHMENT FOR TYPE-WRITERS.

1,300,999.

Specification of Letters Patent. Patented Apr. 15, 1919.

Application filed December 8, 1916. Serial No. 135,866.

To all whom it may concern:

Be it known that I, HYDESABURO OHASHI, a subject of the Emperor of Japan, residing at New York, in the county of New York and State of New York, have invented new and useful Improvements in Inking Attachments for Type-Writers, of which the following is a specification.

This invention relates generally to the class of printing machines and particularly to that type of machine employing or making use of an inked ribbon or ink transferring surface whereby the impression of type can be carried on to a sheet or surface arranged in the presence of the type and more specifically typewriting machines. Ordinarily a machine of this style uses an inked ribbon, a fabric saturated with an ink preparation in which the ink preparation is frequently entirely utilized before the fabric of the ribbon has been destroyed through ordinary use. Owing to atmospheric conditions, certain typewriter ribbons dry out and it becomes impossible to convey to a paper sheet or the like, clear, sharp and strong typewritten impressions. In the present typewriter ribbon the amount of ink contained in the fabric gradually diminishes as the same is used and the type impressions are consequently fainter and lighter. I have therefore constructed an attachment which can be quickly applied to a printing machine such as a typewriter and arranged whereby the commercially inked ribbon can be freely passed over an ink distributer, the ribbon finding frictional confinement against said distributer whereby a new surface of the latter is presented to the ribbon intermittently as the type bars of the machine are actuated, there being associated with the distributer an inking surface which is adapted to permit a quantity of ink to be transmitted to the former to take the place of that body of ink which has been consumed through use or rendered ineffective through drying up. In this manner, means are provided whereby the ribbon will always be possessed with a freshly inked surface so that the type impressions when placed upon the paper sheet will appear strong, and prominent during the entire life of the ribbon. Furthermore, by strengthening the fabric of the ribbon, I can, through use of the present attachment, greatly increase the life of the ribbon.

An important object of the invention re-

sides in the provision of an inking attachment which will be absolutely automatic in its operation to convey to the printing ribbon a small quantity of ink only as the machine is operated, and one which will prevent the feeding of ink to the ribbon when the machine is not in use.

Most typewriting machines now in use are equipped with multi-color ribbons, such as black and red, black and purple or any other variety of distinctive colors, means being included in the machine whereby at the election of the operator a selected color or portion of the ribbon can be accurately associated with the type bars and correspondingly colored written matter set up upon the sheet to be printed. I therefore include in my inking attachment a selective mechanism in which containers for inks of distinguishing colors can be singly advanced into coacting engagement with the distributor above referred to.

A still further object of the invention is to provide an inking attachment in which the ink delivering containers can be rendered inactive relative to the distributor at the will of the operator so that nothing but carelessness on the part of the operator will result in an over inking of the ribbon.

Another object of the invention resides in the provision of an inking attachment which will consist of a principal part including an active distributer or ink receiving surface and a destructible and permanently sealed ink container which is freely removable from the structure whereby when utilized it may be replaced by a new one in an expeditious manner, the container being designed to contain only a sufficient quantity of ink which will be necessary to supply the ribbon with a proper supply of ink during the entire life of the fabric.

With the above and other objects in view which will appear as the nature of the invention is better understood, the same consists in the improved construction and novel arrangement of parts which will be herein-after fully described and particularly pointed out in the claims.

In the accompanying drawings has been illustrated a single and preferred form of the invention, it being, however, understood that no limitations are necessarily made to the precise structural details therein exhibited, but that changes, alterations and modi-

fications within the scope of the claims may be resorted to when desired.

In the drawings:—

Figure 1 is a sectional view through the 5 typewriter in line with the reels, showing the inking attachment applied.

Fig. 2 is an enlarged detail front elevation of the device.

Fig. 3 is a rear elevation of the same.

10 Fig. 4 is a detail view of the ink container.

Fig. 5 is a vertical section through the ink distributor.

The typewriter shown in the drawings is to be considered as merely a method of conveying or illustrating the use of the invention. I do not wish to limit myself to the use of the attachment in connection with typewriting machines as it may be satisfactorily employed in connection with multi-graph machines and in fact any machines employing an inked ribbon from which impressions of the type are adapted to be carried on to a paper sheet or the like. The typewriter includes all of its usual elements 15 such as the spools or reels A and B, and the ribbon guide C, whereby the ribbon can be wound from one of said reels to the other as the occasion demands. In addition to the guide C, the frame D, of the machine includes guide brackets E—E, and passages 20 F, therebeneath through which the ribbon is adapted to pass.

The inking attachment consists of a bracket 1, having a relatively large barrel 35 or cylindrical-like distributor 2, the peripheral surface of which is covered with a pliable material such as rubber or any other composition of matter which will freely receive the ink and then permit the same to be 40 transferred to the ribbon. The distributor is provided with side flanges 3—3, which serve to hold the ribbon uniformly against the periphery of the distributor as will be understood. This distributor is mounted to 45 freely revolve from a shaft 4, carried by the bracket 1. To one side of the distributor are ink containers 5 and 6, the same being arranged in superposed relation and preferably in advance of the ribbon reel A, of 50 the typewriter. Each of these containers is revolvably supported from a shaft 7, mounted upon a rocker 8, the latter having pivotal connection at 9, with the bracket 1. Said shaft 7, extends through an arcuate guide 55 slot 10, in the bracket as clearly illustrated. In this manner, the rockers can be adjusted at the will of the operator whereby the ink containers can be either singly or simultaneously brought into contact with the 60 distributor 2. When it is desired to apply ink to the ribbon, one or both of the containers as may be required, are made to contact with the peripheral surface of the distributor 2. By adhesion the ink will 65 be taken from the containers and delivered to

said distributor, where in turn, it will be distributed to the ribbon. Each of these containers is provided in its periphery at one side of its transverse center with one or more annular series of small perforations 11, the 70 perforations in the container 5 being arranged out of vertical alinement with the perforations in the container 6. These containers are adapted to contain distinctively colored inks, and as a consequence of the described arrangement of perforations, it is 75 evident that two kinds of inks will be applied respectively to two different parts of the surface of the distributor 2. Each container is provided with permanently sealed 80 crowns 12—12, through which the shaft 7, passes loosely. The inner ends of the shafts of said containers have threaded connection in nuts 13, carried by the rockers 8. The outer ends of the shafts are 85 provided with manipulating enlargements which can be conveniently grasped by the fingers when it is desired to apply the containers to or remove the same from said rockers. The ink used in connection with 90 the device is of a rather thick consistency; and in order that it will be fed through the perforations in the containers, I provide the shafts 7, with radial arms 20, having substantially V-shaped ends or heads providing 95 angularly disposed surfaces 20^a, which operate to press the ink against the inner walls of the container and to satisfactorily force the ink through the perforations.

Each rocker is provided with an actuating 100 arm 14 extending beyond one side of the bracket 1, where it may be conveniently moved by hand when it is desired to effect an adjustment of the container with relation to the distributor 2. The nuts 13, have the 105 forward ends of springs 15, connected therewith, while the opposite ends of said springs are connected with the shaft 4. Through this arrangement, the containers are held in 110 positive frictional contact with the peripheral surface of the distributor 2, when said containers are adjusted for the purpose of supplying said distributor with ink. In order to hold the rockers against the action of the springs 15, I provide spring latches 16, 115 upon the bracket 1, having pins 17, which extend through passages in the bracket so that they can come across the portion 14, of the rockers to obstruct the movement of the latter. Slight pressure of the hand 120 against the portions 14, permits the same to freely pass over said pins.

The distributor 2, is arranged in line with the reels A, and as the ribbon is paid from said reel, it is passed over an idle roll 18 125 on the bracket and then over the distributor 2, and finally over a second idle roll 19 on said bracket 1, and thence through the usual ribbon guide passages in the frame of the typewriter. In this manner the ribbon is held 130

in loop form about the distributer and there is always sufficient tension on the ribbon to insure good frictional contact of the same with the inking surface of the mentioned 5 distributer 2.

While I have shown the attachment applied to that design of typewriter machine using a vertically mounted ribbon reel or spool, it is desired that it be fully understood that the same is not to be considered as a necessary limitation. For instance, the 10 attachment will be just as effective for the purpose of applying ink to the ribbon of a typewriter irrespective of the angle or position at which the ribbon reel is supported. 15 That is to say, it can be used in connection with horizontal reels, angularly mounted reels and also inclosed reels as will be understood.

20 I wish also to say that my invention can be applied to a previously inked ribbon as well as to an un-inked ribbon and in the latter instance, the perforations in the container can be enlarged to permit the ink to 25 flow more freely on to the ribbon.

What is claimed as new is:—

1. An inking attachment for typewriter ribbons comprising, a revolubly mounted ink distributer over which the ribbon is adapted 30 to pass, and an ink container revolving against said distributer and provided with means for forcibly causing the ink therein to be discharged on to said distributer on operation of the latter.

35 2. An inking attachment for typewriter ribbons comprising a revolubly mounted ink distributer over which the ribbon is adapted to pass, and an ink container revolving against said distributer and provided with 40 means for forcibly causing the ink therein to be discharged on to said distributer on operation of the latter, and including perforations in the walls of said container and devices positioned in the presence of the distributer and associated relatively of the 45 perforations to press the ink therethrough.

3. An inking attachment for typewriter ribbons comprising a revolubly mounted ink distributer, a perforated ink container arranged in rolling contact with said distributer, and means for supporting the ribbon in frictional contact with said distributer to cause the latter to revolve against the container upon movement of the ribbon 55 through the machine.

4. An inking attachment for typewriter ribbons comprising, a revolubly mounted ink distributer over which the ribbon is adapted to pass and a perforated ink container arranged in rolling contact with said distributer, and provided with means for pressing the ink through the perforations and on to the distributer when the latter is in motion.

65 5. An inking attachment for typewriter

ribbons comprising, a revolving ink distributer disposed in a vertical plane with the ribbon spool, means for holding the ribbon in loop form around said distributer and for feeding the ribbon through the machine from the distributer, mechanism for automatically supplying ink to the distributer as the latter revolves, and comprising, a container having perforated walls adapted to be arranged in free contact with the distributer, and means in the container for pressing the ink through the perforations. 70

6. A ribbon inking attachment for typewriters comprising, a freely revolving ink distributer arranged in a vertical plane with the ribbon spool, means for guiding the ribbon around the distributer, the said distributer having relatively separate inking surfaces, and adjustably mounted ink containers adapted respectively for single and 80 collective contact with the inking surfaces of said distributer.

7. A ribbon inking attachment for typewriter machines, comprising, a revolving distributer having relatively separate inking surfaces, means for looping the ribbon around the distributer, and adjustably supported ink containers respectively disposed in line with said inking surfaces of the distributer and provided with perforated walls 90 by means of which the ink will be discharged on to said inking surfaces as the distributer revolves.

8. A machine for inking ribbons, comprising, a cylindrical revolving ink distributer, means for guiding the ribbon about said distributer to freely cause the same to contact with the periphery thereof, the said means and said distributer operating to hold the ribbon in loop form, means occupying 100 a location within the looped portion of the ribbon and arranged in free rolling contact with the peripheral surface of the distributer for supplying the latter with ink as the former revolves, and mechanism for moving the ink supplying means respectively 105 into and out of engagement with said distributer.

9. A ribbon inking attachment comprising, a revolubly mounted ink distributer 115 over which the ribbon is adapted to pass, means for confining the ribbon against the distributer and a cylindrical ink container supported to revolve against the distributer and arranged out of engagement with the ribbon, and mechanism for moving the ink supplying means respectively into and out of engagement with said distributer.

10. An inking machine for multi-color ribbons comprising revolving means over 120 which the ribbon is adapted to pass, and a battery of cylindrical revolving ink containers for supplying ink to the ribbon as the revolving means is actuated and independently adjusted whereby to be brought 130

- respectively into and out of ink distributing positions relatively of the ribbon, said containers designed to contain inks of relatively different colors, and means for establishing 5 a line of demarcation between the longitudinal edges of the ribbon and for separating the flow of inks from said containers when the latter are in ink delivering position.
- 10 11. An inking machine for ribbons comprising, revolving means over which the ribbon is adapted to pass, and a cylindrical perforated ink container for supplying ink to the ribbon and provided with means for causing the ink to be pressed through the 15 perforations as said revolving means is actuated.
12. A ribbon inking attachment, for typewriters comprising, an ink container, means for revolvably supporting said container 20 from the machine, an ink distributor, and means for supporting said distributor between the ribbon and said container and for holding the ribbon from direct contact with said container. 25

In testimony whereof I affix my signature,

HYDESABURO OHASHI.
